UNITED STATES PATENT OFFICE.

WILLIAM H. GARDINER, OF ALBANY, NEW YORK, ASSIGNOR, BY MESNE ASSIGNMENTS, TO THE PETER SMITH HEATER COMPANY, A CORPORATION OF MICHIGAN.

CAR-STOVE.

1,388,330.

Specification of Letters Patent. Patented Aug. 23, 1921.

Application filed September 20, 1917. Serial No. 192,245.

To all whom it may concern:

Be it known that I, WILLIAM H. GARDINER, a citizen of the United States, residing in the city and county of Albany and State of New York, have invented an improvement in Car-Stoves, of which the following is a specification.

My present invention relates to stoves particularly adapted for heating cars, especially those operated electrically; and it concerns improvements in these devices by which the air is circulated through compartments in the stove by means of a blower, preferably an electrically operated device. After the air is heated it is discharged into ducts which distribute it in the car in well-known ways, not only heating but ventilating the latter.

In the operation of stoves of this character known to me, there has been considerable trouble in adapting the stove to different external temperatures. In general, when efficiently operated to provide for cold weather, there has been great overheating if the temperature outside rises, and as there is a considerable body of fuel in the stove this overheating is maintained for some time. In the arrangement of stove which I prefer, and which is illustrated in the drawings of this case, there are several compartments through which the air may be forced; and these are arranged so that they may be connected in series or in multiple, or one may be shut off, according to the temperature outside. By this arrangement, air is first heated in an external compartment, which is separated from the fire compartment by an interior one, the arrangement being such that the air passes first through the exterior compartment and then through the interior one, absorbing heat from the fire-pot and from the smoke flue, after which it passes into the duct, preferably in the lower part of the car, for distribution as stated. When the temperature rises, however, and the air would otherwise be much overheated, the arrangement of the compartments is different; the one adjacent to the fire-pot and stack is shut off from the draft of air, so that the latter passes only through the exterior compartment of the stove. The air is thus passed through the apparatus at lower temperature, and also in increased quantity, inasmuch as the frictional resistance of this shorter path

is lower than that from the two compartments in series.

In addition to this arrangement I provide means by which, when the blast is shut off, the heated air arising from the natural ventilation of the stove is conducted away from the fan motor, taking a different path from that through which it ordinarily flows when the blast is going. In this way the overheating of the motor is prevented. So far as I know, the ventilation systems of stoves in common use pass the hot air in close proximity to the motor, giving it no chance to cool when the current is turned off from it, and increasing the liability of its burning out.

Another difficulty of stoves in common use has been, that if they provide for different paths for the air when the blast is on and off, the control of this is often tampered with by the car-crew; and even when automatic dampers are used, it is common for the motorman or conductor to block them in fixed position, which of course renders them quite inoperative. My invention obviates this difficulty, because those parts of my stove which are automatic in action are entirely contained within the structure, and are wholly inaccessible to the car-crew.

The means which I employ for regulating the paths of the hot air for different effects or temperatures is necessarily within the control of the crew, however; and may also be so manipulated as not only to provide the two paths required, but to cause part of the air to flow through the longer of them and part through the shorter one, so that the regulation of temperature may be effected by mixing the two to any desired extent. It is also true that in severe weather part of the air to be heated may be drawn from the inside of the car, and mixed in the stove with that from the outside so as not to cause too great a burden upon the stove; this, though undesirable, is sometimes imperative when the weather is very cold.

The accompanying drawings show a stove embodying the ideas set out in my statement of invention, wherein Figure 1 is a conventional perspective of such a stove with parts broken away to show the internal arrangements.

Fig. 2 is a plan of the top plate of such a stove before assembly.

Fig. 3 is a plan of an internal partition hereinafter described.

Fig. 4 is a plan of an interior horizontal plate.

5 Fig. 5 is a plan, and

Fig. 6 an end elevation, of an automatic damper which I use in connection with the blower before referred to.

10 Fig. 7 is a horizontal section approximately upon the lines 7—7 of Fig. 1, with a part broken away to show the arrangement of dampers.

15 In Fig. 1, 1 is a corrugated cast-iron fire-pot of common description, such as is usual in these stoves; 2 is a flue leading from the top of the fire-pot to the stack or smoke-pipe 3, which passes up through suitably protected openings in the top of the car, not shown. 4 is a fire-door and 5 is an ash-pit 20 door, these being provided with the usual draft openings, the use of which is well understood. 6 is an intermediate casing, preferably of heavy sheet iron, which surrounds the fire-pot 1, and between which and the 25 latter is a space, as seen best in Fig. 7. In the illustrated embodiment this casing is substantially rectangular, but obviously may be of any desired form; the rectangular shape of the stove is preferred for its position in most of the trolley cars now in use. 30 7 is the exterior casing of the stove, also preferably of a heavy sheet iron, sufficiently rigid to stand the use to which these devices are put. This is displaced from casing 6 a suitable distance, depending upon the size of 35 the stove (in the case of the one here illustrated this space is about two inches), and the chamber thus formed is divided by a horizontal partition 11, shown in Fig. 1, and 40 in plan in Fig. 3, into upper and lower compartments which form flues or chambers through which the air is forced, as herein-after described. A vertical rod 32 passes from the top to the bottom of the stove 45 through this chamber, and a handle 35 on the outside of the stove rotates the rod, which forms a rock-shaft and carries a damper 13, controlling the upper half of the chamber formed by the partition 11, and 50 mounted at 90° to the damper 13 is a second damper 14, which controls the lower half of this chamber, presently to be more fully described. Mounted upon the rock-shaft 32 is an arm 33; pivoted thereto is a rod 34 extending to a similar set of dampers mounted upon a shaft similar to the shaft upon the other side of the stove; these are in all respects like the dampers 13 and 14 and move simultaneously with the latter when the 55 handle 35 is turned, so that any further description of them is unnecessary. Controlled by the damper 14 is an opening 15 in the casing 6, as presently to be more fully described when I trace the course of the air 60 currents in the stove. 65

The top of the compartment formed in part by casing 6 is partly closed by the horizontal partition, shown also in plan in Figs. 4 and 7, having a duct 16 through which passes the flue 2. This plate or casing 9 closely approximates the casing 7 on the sides, but at the front and the back there is a space between it and the inclosure so that the air may pass. The casing 6 is closed at the front by a plate 25, which may 70 upon occasion be removed by removing the bolts 25^a securing it to the casing 6; and the front of the stove is closed by a plate 27, which may similarly be removed by removing the bolts 27^a and the casing of the fire-door, which is effected by taking out the bolts 4^a. When these two plates and the cast-iron fire-door are removed, the entire 75 interior of the compartment formed by the casing 6 is exposed, and the fire-pot may, if desired, be removed without disassembling the rest of the stove or taking down the motor or any of its adjuncts.

80 The top of the stove is closed by the horizontal plate 10, which is shown also in plan in Fig. 2. This contains an opening 24 through which the blast of the fan passes, as presently to be described; an opening 30, through which passes the smoke-pipe 3 and to which is connected the flue 2; and two 85 openings 29, which are closed when the fan is in action and open when it is idle. These will be referred to later. Mounted upon the top plate 10 is a housing 17, preferably a casting. This contains an opening at the 90 top, as indicated in the part which is broken away, through which the smoke-pipe 3 passes, and between it and the pipe is a space of half an inch or so. Surrounding the pipe is a collar 31, disposed above this 95 opening, but not close enough to it to obstruct the flow of air in and out of it. In the interior of the housing is a vertical partition 22, containing the orifice 22^a, through 100 which air passes to the fan 23, driven by the motor 26. A second housing 20, which 105 may be formed separate or be made integral with the housing 17, covers an opening 19 through which air may enter from a duct 21, passing through the wall 38 of the car. 110

115 Between the horizontal plates 9 and 10 is mounted the automatic damper 12, shown also in plan in Fig. 5, and in end elevation in Fig. 6. This damper is mounted upon the rod 12^a and is provided with weighted 120 flaps 12^b; it is so arranged that the weights slightly overbalance the front part of the damper, and when the fan 23 is idle, the damper closes the hole 24 and the weighted flaps open the holes 29—29 in the top plate 125 10. When, however, the fan starts up the blast of air therefrom pushes down the front end of the damper 12, and the flaps are elevated and close the holes 29. It will be observed that this damper is completely in- 130

closed within the stove, and is wholly inaccessible from the outside without opening the front of the stove by removal of the plate 27 and fire-door 4. Thus it is impossible for the car crew to block it open or closed or otherwise to tamper with the arrangement of the stove. Of course it is contemplated that upon occasion lever 35 will manipulate the dampers 13 and 14, as now to be described.

The course of the air currents may best be determined from Figs. 1 and 7. The dampers are set in Fig. 1 for maximum heating effect, the course of the current when the fan is running being as follows:—Air is drawn in through the duct 21 from the outside of the car and also to a less extent from the inside of the car through the opening between the housing 17 and the smoke-pipe 3. Air then passes through the opening 22^a into the fan, and is by it driven against the damper 12, opening the hole 24 in the top plate 10 and closing the holes 29—29, as previously explained, by the tilting upward 25 of the flaps 12^b of the damper 12. The air then passes down between the walls 25 and 27 in the front of the stove and around the corner of the casing 6, as the space between it and the front plates of the stove is arranged to be of sufficient size to permit the passage of the draft into the chamber between the casing 6 and the outside casing 7 of the stove. With the arrangement of dampers 13 and 14 shown in Fig. 1, the lower 30 part or duct of this casing is closed against the direct draft of air by the damper 14, and the upper part is opened by the damper 13. The air then passes around between the upper parts of casing 6 and casing 7 to the 35 back of the stove, thence up between the back of the stove and the top plate 9; thence it passes through the duct 16 around the flue 2 and the fire-pot 1, being forced to the bottom of the stove, whence it passes through the opening 15 in the casing 6 and is forced 40 out through the duct 8, to be distributed through the car. The course of the draft on the opposite side of the stove is precisely identical, as will be evident from considering the sectional view, Fig. 7. When the 45 stove is located in the center of the car, ducts 8 may extend from each side thereof; but when, as is common, it is located near one platform, there is only one of the ducts 50 8, and all of the air will be forced out through the said duct.

When, however, the weather is milder and so much heat is not desirable, the handle 35 is pushed toward the back of the stove for 55 90°; this will turn the damper 13 across the opening through the upper flue between the casing 6 and the casing 7 and will also open the lower flue by turning the damper 14, as indicated by the dotted lines; and will 60 close the opening 15 in the casing 6. Under

these conditions the air does not pass down the duct 16 and around the fire-pot and the flue 2, but passes only adjacent to the plate 25 and casing 6, whence it flows out through the lower part of the chamber, between casing 6 and casing 7, directly into the duct 8. It will be obvious that by adjusting the position of the handle 35 a part of the air may be permitted to pass into the upper chamber and around through the chamber 70 75 containing the fire-pot, and the same position of the handle 35 will open the hole 13 partway, so that the two drafts will be blended and the temperature regulated as nicely as may be desired.

When the fan is stopped, however, the damper 12 rises and closes the opening 24. Under these conditions the natural or convection draft of the stove causes the air to rise and pass through the openings 29 in 80 85 the plate 10, blending to a greater or less extent with the draft from outside through duct 21. There it passes out through the opening between the housing 17 and the smoke-pipe. It will be observed that by this 90 arrangement no part of the hot air passes over the motor 26, but the discharge thereof is above the motor and away from it, so that there is only the radiation from the stove to be provided for. Such radiation to 95 a great extent is cut off by means of the shield 28, interposed between the stove and the motor, thus effectively preventing the overheating of the latter. Of course when the fan is running there is a slight suction 100 through the opening between the housing 17 and the smoke-pipe.

Changes may be made in the arrangement without departing from the invention. I have not thought it necessary to illustrate 105 or describe a sliding damper in the duct 21 to regulate the amount of external air admitted, or the means connected with the duct 8 for distributing the air through the car, since they are old and well known.

What I claim is:

1. In a car stove, the combination of a fire-pot, a plurality of air-heating chambers surrounding it, a fan and means for conducting a blast of air from the fan through 115 the surrounding air-heating chambers in series, or for cutting out part of them at will.

2. In a car stove, the combination of a fire-pot, an air-heating chamber surrounding it, a second air-heating chamber surrounding 120 the first, dampers controlled from outside the stove and acting in one position to connect the chambers in series, and in another position to open one of the chambers and close another; and a fan for passing a blast 125 of air through one or both of the chambers according to the position of the dampers.

3. In a car stove, the combination of a fire-pot, an air-heating chamber surrounding it, a second air-heating chamber surround- 130

ing the first and divided into a plurality of ducts, one of which communicates with the first chamber and another of which communicates with the car interior; a fan, and 5 means for conducting the blast from the fan through the ducts in a desired relation.

4. In a car stove, a heating means, a chamber surrounding it, a second chamber surrounding the first, the second chamber being 10 divided into upper and lower ducts; dampers for opening and closing the ducts at will, and a fan for passing a blast of air through the ducts; the arrangement being such that the dampers may connect the lower 15 duct to the chamber surrounding the heating means near the bottom of the latter, and the upper duct to the said chamber near the top thereof, thus passing the blast of air through the upper duct, the chamber surrounding 20 the heating means and the lower duct; or by shifting the dampers, cutting out the upper duct and the chamber surrounding the heating means; or by placing the dampers in an intermediate position, permitting a part of 25 the blast to pass through the ducts and the heating chamber in series, and part of it to be diverted through the lower duct, thus blending the two parts of the blast and tempering the air, as desired.

30 5. In a car stove, a fan, a motor driving it, an opening in the top of the stove above the motor through which the natural draft of the stove may pass when the fan is idle, and means, automatically operated by the stopping of the fan, for directing the draft of air through such opening.

6. In a car stove, a fan, a motor driving it, an opening in the top of the stove above the motor through which the natural draft 40 of the stove may pass when the fan is idle, and means, automatically operated by the stopping of the fan for directing the draft of air through such opening, such means comprising a balanced damper, operated by 45 the blast of the fan, and wholly inclosed within the stove.

7. In a car stove, the combination of air heating means, a chamber surrounding said means, a fan for delivering air to said chamber, a plate covering the chamber and provided with two sets of openings, and a balanced damper operated by the starting and stopping of the fan; the damper acting when the fan is in operation to close one set of 50 openings in the plate and to open another, and when the fan is idle to open the second openings and close the others.

8. In a car stove provided with ducts through which the air may be passed when 60 heated, two dampers set at an angle to each other upon the same rod, one damper acting to control one of the ducts and the other damper to control the other duct, the arrangement being such that with the dampers 65 in one position the current of air will pass

through the two ducts in series, and with the dampers at 90° from such position one of the ducts will be cut out, and the current will pass through the other one only; and when the dampers are in intermediate position, part of the current will pass through both ducts in series, and part through one only. 70

9. In a car stove, the combination with air heating means, of inner and outer air 75 heating chambers surrounding the heating means, a partition forming upper and lower ducts in the outer chamber, one of said ducts having an outlet to the inner chamber and the other duct having an inlet thereto from the inner chamber and having a discharge opening, means for delivering air under pressure to said ducts, and a damper adjustable to positions for respectively cutting off the air supply to the duct having the discharge 80 opening and for closing the inlet to said duct from the inner chamber.

10. In a car stove, the combination with an air heating means, of inner and outer air 90 heating chambers surrounding the heating means, a partition forming upper and lower ducts in the outer chamber, one of said ducts having an outlet to the inner chamber and the other duct having an inlet thereto from the inner chamber and having a discharge 95 opening, means for delivering air under pressure to said ducts, a damper adjustable to positions for respectively cutting off the air supply to the duct having the discharge opening and for closing the inlet to said duct from the inner chamber, a damper controlling the air supply to the other duct, and a common control means for said dampers.

11. In a car stove, the combination with an air heating means, of a casing inclosing 105 said heating means, said casing having an inlet for air under pressure and an outlet for convection air currents rising when the pressure is discontinued, a damper having positions for respectively closing said openings balanced to open said inlet and close said outlet when subjected to the pressure of incoming air and to close said inlet and open the outlet when the pressure is discontinued. 110

12. In a car stove, the combination with an air heating means, a casing inclosing said heating means provided with air heating ducts arranged for connection in series, means for delivering air under pressure to 120 said ducts, dampers respectively controlling the air supply to said ducts connected to establish a supply to one of the ducts when cutting off said supply to the other one of said dampers acting to establish or cut off 125 the flow of air in series through said ducts according as it cuts off or establishes the air supply to the duct which it controls.

13. In a car stove, air heating means, inner and outer air heating chambers secur- 130

- ing said means, means for compelling a flow of air into the outer chamber, a passage for discharging the heated air from the stove and valve mechanism for effecting a connection of the outer chamber with said discharge passage independently of the inner chamber, or establishing a flow of air from the outer chamber through the inner chamber to said discharge passage.
- 10 14. In a car stove, the combination with air heating means, with inner and outer air heating chambers surrounding said means, a partition forming upper and lower ducts in one of said chambers, one of said ducts having an outlet to the other chamber and the other duct having an inlet thereto from said other chamber and having a discharge opening, means for delivering air under pressure to said duct, and a damper adjustable to positions for respectively cutting off the air supply to the duct having the discharge opening and for closing said inlet to said duct.
- 15 15. In a car stove, the combination with an air heating means, of inner and outer air
- heating chambers securing said means, a partition forming an upper and lower duct in one of said chambers, one of said ducts having an outlet to the other chamber and the other duct having an inlet thereto from 30 said other chamber and having a discharge opening, means for delivering air under pressure to said ducts, a damper adjustable to positions for respectively cutting off the air supply to the duct having the discharge 35 opening and for closing the inlet to said duct, a damper controlling the air supply to the other duct and a common control means for said dampers.
16. In a car stove, a fan and motor driving the same surmounting the stove, a smoke stack rising from the stove, a housing surrounding the stove and surrounding said stack, and means automatically operated by stopping of the fan for directing the con- 40 vention current of air into said housing.
- In testimony whereof, I have signed my name to this specification this 13th day of September 1917.

WILLIAM H. GARDINER.
